ATTORNEYS

UNITED STATES PATENT OFFICE.

JOHN STUTTER, OF MASPETH, NEW YORK.

FENCE CONSTRUCTION.

Application filed January 29, 1925. Serial No. 5,504.

To all whom it may concern:

Be it known that I, JOHN STUTTER, a citizen of the United States of America, and resident of Maspeth, borough of Queens, in the county of Queens and State of New York, have invented a new and Improved Fence Construction, of which the following is a full, clear, and exact description.

This invention relates to a fence construction and refers more particularly to wire or wire fabric fences, although the same is not necessarily limited to the same.

Among the outstanding objects of the present invention is the provision of a fence made up of separate units disposed between each adjacent pair of supports and in which each unit consists of a pair of sections detachably connected at their inner ends with each other and detachably connected at their outer end with the fence supports whereby a passageway between any pair of adjacent supports through the length of the entire fence may be readily made when occasion demands.

Further objects flowing from this construction of fence reside in the facility with which the same may be erected; the elimination of the necessity of using stretchers for erecting the same; the economy with which repairs to a broken unit or section may be accomplished; and the provision of means for compensating for contraction and expansion due to varying atmospheric conditions.

With the above recited and other objects in view, the invention resides in the novel construction set forth in the following specification, particularly pointed out in the appended claims and illustrated in the accompanying drawings, it being understood that the right is reserved to embodiments other than those actually illustrated herein, to the full extent indicated by the general meaning of the terms in which the claims are expressed.

In the drawings—

Figure 1 is a side view of a portion of the fence constructed in accordance with the invention.

Fig. 2 is an enlarged fragmentary view illustrating a portion of the inner connected ends of the fence unit sections and showing in broken lines a tool for effecting the connection and disconnection of the fence unit sections.

Fig. 3 is an enlarged detail horizontal sec-

tional view taken approximately on the line 3—3 of Fig. 1.

Fig. 4 is an enlarged vertical sectional view taken approximately on the line 4—4 of Fig. 1.

Referring to the drawings by characters of reference the fence consists of vertical longitudinally spaced supporting members 10 which are preferably in the nature of channel shaped posts having spaced parallel sides 11 connected by a bight portion 12 which is disposed in a plane parallel to the length of the fence. Between each adjacent pair of supports or posts 10 a fence unit designated generally by the reference character 13 is supported or stretched and each of said units comprises a pair of identical sections designated generally by the reference characters 14—14. Each section of each fence unit is provided at its inner end with eyes, loops or hooks 15 and at its outer end with similarly formed eyes, loops or hooks 16. The eyes, loops or hooks 16 are inserted through slots 17 in the sides 11 of the channel shaped posts 10 and rods or other retaining elements 18 are passed therethrough to detachably lock the outer ends of the sections in connected relation to the posts or supports 10. In order to provide means for detachably connecting and maintaining the inner ends of the sections 14 in connected relation and under tension, contractile connector elements 19 are employed which are preferably in the nature of coiled contractile springs having hooked opposite end terminals 20 engageable in the eyes, loops or hooks 15 at the inner ends of the sections 14, said connection being made with the elements 19 under tension or stretched. In order to facilitate the expansion or stretching of the elements 19 during the application and removal, the said elements between their hooks terminals 20 and their end convolutions are provided with eyes 21 to receive the terminals A of the jaws of a substantially plier-like tool B.

From the foregoing construction and arrangement it will thus be seen that a fence of this type admits of the ready connection and disconnection of the unit sections to afford a passageway through any pair of adjacent posts whereby ingress or egress may be accomplished. Furthermore damage to any unit or unit section facilitates the ready repair of said section or unit at a minimum expense while the remainder of the fence is in no

way affected. The construction further admits of the construction of the fence by a single person or workman without the use of a fence stretching device as is the case with 5 an unbroken line wire fence.

I claim:

1. A wire fence including a plurality of spaced vertical supports and individual fence units between each pair of adjacent supports, each of said units comprising a pair of sections, each section including a plurality of horizontal and vertical wires connected at their points of crossing, said sections having detachable connections at their outer ends with the supports, and detachable connections at their inner ends with one another, said latter connections being contractible and normally expanded when in place to set up a tension upon the sections.
2. A wire fence including spaced posts and individual fence units between each adjacent pair of posts, said units each comprising separable sections, each section including a plurality of crossed and connected wires, means for detachably connecting the outer end of each section to a post and contractile spring links for detachably connecting the inner ends of the sections together.
3. A wire fence including spaced posts and individual fence units between each ad-

jacent pair of posts, said units each comprising separable sections, said sections each comprising a mesh of crossed and connected wires, means for detachably connecting the outer ends of each section to a post, and 35 means for detachably connecting the inner ends of the sections together, said means consisting of a plurality of contractile spring links, said links being normally expanded and under tension when in connected relation to the sections, whereby to hold said sections taut while permitting the disconnection of the sections of any unit to provide a passageway between any pair of adjacent posts.

4. A wire fence including spaced posts and individual fence units between each adjacent pair of posts, said units each comprising separable sections of wire mesh, means for detachably connecting the outer 50 end of each section to a post, contractile spring links for detachably connecting the inner ends of the sections together, the terminals of the links detachably engaging the ends of the sections, and means adjacent the terminals of the links for receiving an expanding tool for stretching the links to facilitate their attachment or detachment.

JOHN STUTTER.
